UNITED STATES PATENT OFFICE.

HENRY S. HORNBECK, OF UNION HILL, NEW JERSEY.

PNEUMATIC PICK-UP.

1,399,483.

Specification of Letters Patent.

Patented Dec. 6, 1921.

Application filed July 22, 1920. Serial No. 398,119.

To all whom it may concern:

Be it known that I, HENRY S. HORNBECK, a citizen of the United States, residing in Union Hill, in the State of New Jersey, have invented certain new and useful Improvements in Pneumatic Pick-Ups, of which the following is a specification, reference being had to the accompanying drawings, forming a part hereof.

In the operation of pneumatic press feeders, in which each sheet of paper to be fed to the press is lifted by one or more pneumatic or suction pick-ups from a pile of sheets, it sometimes happens that the second sheet is picked up or at least displaced along with the top-most sheet, as the result, it may be, of cohesion between the sheets, or of electrical conditions, or of the formation of a partial vacuum between the sheets by the initial separation of the two sheets. It is the object of this invention to improve the construction of such pick-up fingers so as to prevent this occurrence and to assure the complete separation of the top-most sheet from the second sheet without displacement of the second sheet. To this end the suction pick-up is provided with a projection, extending slightly beyond its working face, which, acting through the top-most sheet, holds the second sheet down and in place during the initial lifting of the top-most sheet and its separation, around the point of pressure, from the second sheet. The invention will be more fully explained hereinafter with reference to the accompanying drawing in which it is illustrated and in which—

Figure 1 is a view in vertical section of so much of a pneumatic press feeder as is necessary to enable the application thereto of the improved pick-up to be understood.

Fig. 2 is a detail view, on a larger scale, in transverse section, of the improved pick-up, showing its relation to the pile of sheets after it has moved into working position but before suction is applied.

Fig. 3 is a detail view of the same partly in elevation and partly in section on a plane at right angles to that of Fig. 2, a portion of the tube being shown in elevation and partly in section.

Fig. 4 is a partial detail view similar to Fig. 2 but showing the relation of the pick-up to the top-most and second sheets after suction has been applied to the pick-up but

before the transporting movement of the pick-up has begun.

The feeder or mechanism to which the pick-up, for purposes of illustration, is shown as applied, is in general such as that shown and described in an application of the present applicant for Letters Patent of the United States for improvements in feeders for printing presses, etc., Ser. No. 269,054, filed December 31, 1918. To enable the present invention to be understood, it is sufficient to say that the lifter or lifters, or pick-ups and their operating devices may be supported by a suitable casing *a*, each suction cup or pick-up *b* (of which there may be several), being supported by and in communication with a pipe *b'*, connecting through a pipe *b*² in a vertical plane with a horizontal pipe *b*³. The last named pipe is movably supported in a swinging frame or carrier *c* and is connected through an air way and flexible tube *c*⁴ and controlling devices *c*⁵ with the main wind-way or suction box *a*⁹, which is connected to any suitable means for creating suction or vacuum. The pipe *b*³ is oscillated in its bearing in the carrier *c* through suitable connection with a bellows *e*³ and the carrier *c* is itself actuated through suitable connections to a bellows *f*', whereby the movement of the tube *b'* and pick-up *b* to the working or pick-up position and in transporting the sheet, when picked up, to the place of delivery is effected. It will be understood that the air connections between the pick-up *b* and the suction box are suitably controlled so that suction is applied to the pick-up as soon as it reaches its working or pick-up position, indicated in Figs. 1, 2 and 3, and is released as soon as the pick-up reaches the delivery position.

As shown, the suction cup or pick-up *b* is formed with the pipe *b'* and is connected therewith internally through a bore *b*⁴, which communicates preferably with an enlarged recess *b*⁵ in the working face of the pick-up. If constructed as already described, the application of suction to the pick-up would lift the topmost sheet of the pile and would often lift with it the second sheet, as stated above. To prevent this action there is provided in working relation with the face of the pick-up a projection *b*⁶, which extends slightly beyond the plane of the working face of the pick-up, sufficiently to hold the top-most

sheet down at the point of contact and therefore to hold the second sheet down also at the corresponding point, when the suction is first applied to the pick-up. The extent of 5 projection, however, is not sufficient to prevent the suction from lifting the top-most sheet into contact with the working face of the pick-up and therefore, as shown in Fig. 4, to separate the top-most sheet slightly 10 from the second sheet in the vicinity of the point of contact of the projection with the top-most sheet, thereby initiating the separation of the top-most sheet from the second sheet before the transporting movement of 15 the pick-up begins and while the second sheet is held in position by the pressure of the projection. The projection can be arranged in any convenient relation with respect to the working face of the pick-up, provided it is in 20 relatively close proximity to such working face and in action is in rigid relation therewith, but is preferably arranged centrally

with respect to the recess b^5 , that is, within the boundary thereof, and is carried by a screw threaded rod b^7 adjustably supported 25 in the pick-up by a threaded sleeve b^8 and nut b^9 , so that the extent of the projection beyond the working face of the pick-up can be regulated to suit different conditions of use. It will be understood, however, that 30 various changes can be made in the form of the pick-up and in the form and arrangement of the projection to suit different conditions.

I claim as my invention:

The combination with a suction pick-up 35 having a recess in its working face, of a rod extended centrally through the recess and projected rigidly beyond the plane of the working face and within the boundary thereof.

This specification signed this 19th day of July, A. D. 1920.

HENRY S. HORNBECK.
